(57) **CLAIM**

The ornamental design for a cake stand, as shown and described.

DESCRIPTION

FIG. 1 is an isometric view of a cake stand showing my new design; it being understood that the broken lines showing a bride and groom and cakes are for illustrative purposes only and form no part of my claimed design.

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.
